No. 118.

W. C. Crosson, Owner
Dated May 25, 1870.

1

Wm P. Cresson, Philadelphia Penna
Letters Patent (Design No 48) dated 23 May 1846.

Dec. 48

The Schedule referred to in these Letters Patent and
making part of the same

To all whom it may concern: Be it known
that I, William P. Cresson of the City of Philadelphia in the state
of Pennsylvania, have invented or produced a new and useful design
for a summer furnace, and I do hereby declare that the following
is a full and exact description thereof.

My summer furnace is in its general form, cylindrical,
and it is to be made of cast iron, there being ornamental devices
on the patterns thereof, the nature of which, as well as the shape
or configuration of the furnace are shown in the accompanying
drawings. Fig. 1 is a top view of my furnace, fig. 2, is a side
and fig. 3 a front view of it; A A being a trivet, or open work-
casting, to sustain the articles that are to be placed over the fire.
B B represents the ornamental rim of leafing which surrounds
the upper part of the cylindrical body of the furnace. The cylindrical

2

Des 48

body consists of four panels, each constituting one fourth of a hollow cylinder; three of these are cast from the same pattern and have on them the same ornamental device. This device consists of the scroll work, flower work, & leafing, shown at C C. The fourth panel shown in fig. 3, is the front of the furnace which is furnished with a door D ornamented as represented, and this is surrounded with an ornamental device such as is shown at E E.

F is the top, or hearth of the furnace the outer edge of which has a leafing around it such as is shown at C C this same ornamental leafing is continued around the bottom plate of the furnace.

I have thus described and represented the respective parts of my newly designed summer furnace showing the ornamental design used thereon, and the general shape or configuration thereof, and I do hereby claim the exclusive right to the said ornamental designs as displayed on a summer furnace of the shape or configuration of that herein described and represented.

Witness,

J. Mitchell
